ATTORNEY.

UNITED STATES PATENT OFFICE.

LOUIS PHILIP WELLMANN, SR., OF UNION HILL, NEW JERSEY, ASSIGNOR OF ONE-FOURTH TO FRANCES BERTHA VICTORIA WELLMANN, ONE-FOURTH TO CHARLES HENRY WELLMANN, ONE-FOURTH TO LOUIS PHILIP WELLMANN, JR., AND ONE-FOURTH TO HARRY EDWIN WELLMANN, ALL OF UNION HILL, NEW JERSEY.

RIDING SADDLE.

Application filed June 27, 1923. Serial No. 648,148.

To all whom it may concern:

Be it known that I, LOUIS PHILIP WELLMANN, Sr., a citizen of the United States, residing at Union Hill, county of Hudson, 5 and State of New Jersey, have invented a new and Improved Riding Saddle, of which the following is a specification.

This invention relates to racing saddles and has for its primary object to provide a 10 light and highly efficient saddle particularly designed for race horses and polo horses.

The primary object of my invention is to provide a racing saddle which may be positioned over the shoulders and secured 15 over the withers thereby permitting the jockey to shift his weight from the withers to the neck of the animal so that greater speed is obtained, since by shifting the weight off the hind legs and middle of the 20 back to the neck of the animal, the horse does not tire so quickly.

In the present type of horse racing saddles, they are usually set on the horse's ribs from the withers back to the hips of 25 the horse. Consequently, the weight of the jockey and the saddle over the weakest part of the horse's back and over the kidneys causes the hind driving legs to tire sooner than if the weight was thrown forwardly 30 of the withers to the neck and shoulder blades. Experience in horse racing has taught the jockeys to shift their weight by standing on the stirrups but the present type of saddles now used are such as to hinder 35 the jockey in his desire to get the greatest speed out of a horse in close competition.

I accomplish the above objects in providing a saddle wherein the seat may be shifted back and forward from the withers to the 40 neck and shoulder blades of the animal, wherein the stirrups may also be adjusted so that the weight or pressure of the jockey as he rises from his seat, is carried by the neck and shoulder blades, consequently permitting the horse to exert the greatest effort 45 with the least hindrance as when racing against time.

To enable others skilled in the art to fully comprehend the underlying features of my 50 invention that they may embody the same in the various modifications in structure and relation contemplated, drawings depicting a preferred form have been annexed as a part

of this disclosure and in such drawings, similar reference characters denote corresponding parts throughout all the views, of which,

Figure 1 is a view showing the saddle positioned on the animal and the normal position of the jockey seat.

Figure 2 is an enlarged view showing the saddle removed.

Figure 3 is a plan with the jockey seat removed.

Referring now to the drawings wherein like reference characters designate corresponding parts throughout all the several views, the saddle comprises the metal frame consisting of two trussed saddle bars 5, 6, which may be formed of light, hollow tubing 70 connected at their rear ends 7, thus forming a triangle. Each trussed bar 5, 6, is bent upwardly as at 8, 9, at an angle of approximately 30 degrees, the upwardly bent bars 10, 11, being also connected at their inner 75 ends 12, forming a similar triangle. It will be noted that this frame work is in the form of a truss and that the inner ends of the bars 10, 11, are disposed at a point approximately between the apex of the triangle 80 and the foot of each of the bars 5, 6. The frame is so constructed that the weight of the jockey will be disposed at the central portion of the truss or frame and which as shown in Figure 1, is over the withers of 85 the animal. If so desired, the side bars 5, 6, may be connected at their apex by a staple for instance and that the bars 10, 11, may in turn be connected thereto by staples, if, in practice, this arrangement is more 90 convenient for assembling the frame.

The side bars 5, 6, are connected to the bars 10, 11, respectively by a plurality of equally spaced reinforcing or connecting rods or bars 13 which form spaces 14 at the forward end of the truss bars 5, 6, to which the straps 15 of the stirrups 16 may be attached and at the convenience of the jockey. In other words the height of the jockey will determine just at which position on the trussed bars 5, 6, he desires the stirrups be attached. The neck piece 17 is connected to the inner bars 10, 11, by the usual form of buckles and straps 18, in the manner clearly indicated by Figures 2 100 and 3 of the drawings. The frame work

and particularly the connections 7, 12, of the bars 5, 6 and complementary bars 10, 11, are joined by a downwardly extending reinforcing tube or bar 20. In order to prevent the frame work from tilting or slipping, an arch 21 is provided between the bars 5, 6, and beneath the connection 12 of the inner bars 10, 11, which arch supports the cushion 22 resting on the sides of the withers. The breast girth 23 and strap 24 may be adjusted by the usual buckle 25, it being noted that this feature of the saddle permits it to be securely set at a point over the withers. The rear girth 26 is also provided with the strap and buckle 27 which retains the rear end of the frame close to the body of the horse. In the event that the neck piece be torn, in order to offset the possibility of the front ends of the stabilizer bars being forced downwardly due to the pressure on the stirrups, the rear strap 26 prevents this movement of the saddle bars as shown. The seat proper 28, is supported in the parallel, longitudinally extending bars 29, 30, being so arranged that the seat or saddle may be moved backwardly and forwardly and thus shift the weight of the jockey when in a sitting position from the withers toward the neck of the animal.

The frame work of the saddle as above described when constructed of light tubing, such as aluminum, for instance, or other metal which permits of brazing the various parts, is as light, if not lighter, than the conventional type of leather saddle and affords greater latitude for the exercise of riding skill on the part of the jockey in that the weight, which is a primary factor in horse racing may be shifted, to accomplish the purposes set forth.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention what

I claim as new and desire to secure by United States Letters Patent is:—

1. A saddle of the class described comprising a trussed frame, a neck piece connected to the frame, a seat, and a girth for positioning the frame over the withers. 55

2. A saddle of the class described comprising a trussed frame, a neck piece connected to the sides of the frame, a seat mounted substantially centrally of the frame, and a girth for positioning the said frame over the withers. 60

3. A saddle of the class described comprising a triangular frame, the sides of said frame extending inwardly and upwardly toward each other forming a truss, means for bracing the truss, a neck piece attached to the frame, a seat mounted on the trussed frame rearwardly of the neck piece, and a 70 girth for positioning the said frame over the withers. 65

4. A saddle of the class described comprising two connected saddle bars disposed in the same plane and forming a triangle, each of said bars extending upwardly and inwardly toward each other forming a similar triangle, reinforcing bars connecting the sides of the triangles producing a trussed frame, a seat support mounted on the apex 80 of the inner triangle, a seat on the support, and a girth for positioning the said frame over the withers. 75

5. A saddle of the class described comprising two connected saddle bars forming 85 a triangle, each of said bars extending upwardly and inwardly to a point substantially intermediate the apex and base and forming a similar triangle, a plurality of spaced reinforcing bars connecting the triangles and constituting therewith a trussed frame, a reinforcing bar connecting the apices of the said triangles, a neck piece attached to the legs of the inner triangle, a seat support mounted on said inner triangle substantially centrally of the frame, a girth, and a body belt for positioning the frame over the withers. 90 95
